HUBERT K. KRANTZ, OF ROCKVILLE CENTER, NEW YORK, ASSIGNOR TO WESTINGHOUSE ELECTRIC & MANUFACTURING COMPANY, A CORPORATION OF PENNSYLVANIA

SWITCH MECHANISM

Application filed August 11, 1928. Serial No. 298,696.

My invention relates to switch mechanism and particularly to switch mechanism of the tumbler action type wherein a bridging switch is pivotally mounted for engaging spaced contact members and wherein a pivoted operating handle is connected to the switch member by an over-center spring for causing the switch to move to open and closed positions with a snap action in response to a predetermined movement of the operating handle.

An object of my invention is to provide a tumbler type switch suitable for controlling the circuits of distributing panels, wherein the switch is mounted upon an insulating base member and wherein the contact members of the switch extend beneath the insulating base member and engage terminal members that are mounted upon the distributing panel base, and wherein the attaching bolt which usually serves to connect the switch to the panel base, serves also to connect the contact members of the switch to the terminal members of the base.

A further object of my invention is to provide a tumbler type switch having the above-noted characteristics wherein many of the parts may be stamped from sheet metal and wherein assembly thereof is facilitated.

These and other objects that will be made apparent throughout the further description of my invention are attained by means of the switch mechanism hereinafter described and illustrated in the accompanying drawing, wherein:

Figure 1 is a side elevational view of a switch embodying features of my invention and showing the switch parts in the position they occupy when the switch is in closed position.

Fig. 2 is an elevational view, similar to that of Fig. 1, showing the parts in the open position.

Fig. 3 is a side elevational view of the switch viewed from the side opposite to that of Fig. 1.

Fig. 4 is a top plan view of the switch shown in Fig. 1; and

Fig. 5 is an end view of the switch with the parts in the open position as shown in

Fig. 2, the drawing being in reduced scale.

Referring to the drawing, the switch comprises an insulating base member 6, preferably made of micarta or other fibrous insulating material upon which is mounted a frame 7 that is stamped from sheet metal and consists of a base portion 8 and wing portions 9 that extend normal to the base portion and parallel to one another as indicated in Fig. 5. The base portion 8 is secured to the insulating base 6 by means of rivets 11 and the frame is provided with a deep notch 12, Fig. 3, that extends inwardly from the base portion for receiving a switch carrier 13 that is stamped from sheet metal and is of U-shape as indicated in Fig. 5. The wings 9 of the frame 7 are provided with bearing portions 14 that are located adjacent one side of the notch 12 as indicated in Fig. 3, the bearing portions being provided with bearing openings 15 for receiving inwardly extending journals 16 that project into the bearing openings 15. The journals 16 serve as a pivot about which the carrier 13 may oscillate within the notches 12, the sides of which at 17 serve as limit stops for the carrier.

A pair of yielding switch blade members 18 are secured to the outer edge of the carrier 13 upon an extension 19 and a pair of arc extinguishing plates 21 are also mounted upon the extension 19 on opposite sides of the switch blades 18, the insulating plates being disposed between metal washers 22 mounted on the extension 19. The switch blades and insulating plates are secured to the carrier by peening over the end of the extension 19.

A pair of contact members 23 and 24 are aligned with the switch blades 18 in such manner that when the switch blades are moved to the closed position shown in Fig. 1, the blades engage opposite sides of the contact members. The contact members 23 and 24 are provided with terminal engaging portions 25 that extend beneath the base member 6 and are adapted to conductively engage terminal straps 26 that are mounted upon the insulating panel base 27 as shown in Fig. 3. The base 6 and the terminal engaging portions 25 of the contact members are provided with

notches 28 for receiving attaching screws 29 that are secured to the insulating panel base 27 and serve to clamp the contact members 23 and 24 and the insulating base 6 to the distributing panel base 27. When the switch blades are in the closed position, the terminals 26 are conductively connected. One of the terminals 26 may be connected to a load circuit and the other to a fuse receptacle. By reason of this construction, the switch is attached to the distributing panel base and to the conductive terminals with one operation.

The switch carrier 13 is actuated by means of an insulating operating handle 31 that is pivotally mounted upon a shaft 32 that is supported in the wings 9 of the frame. A pair of operating arms 33 are also pivoted upon the shaft 32 and are disposed on opposite sides of the handle 31 in recesses 34 in the sides of the handle. Since the notches 34 are non-circular and since the arms 33 and operating handle 31 are pivoted upon the shaft 32, the arms are retained in assembled position between the wings 9 and move with the switch operating handle. The arms 33 are provided with openings 35 which receive inwardly extending lugs 36 mounted on the free ends of the carrier 13. The openings 35 provide a limited lost motion connection between the operating handle and the carrier 13, but the cooperating parts are so related that the operating handle may positively move the switch blade to either open or closed position after the operating handle has moved a predetermined distance in either direction.

In order to cause the carrier 13 to be moved to open and closed positions with a snap action, the arms 33 of the operating handle 31 are connected to the carrier 13 by means of an over-center compression spring 37 that is mounted upon a pintle 38 having an enlarged forked end 39 provided with a notch 41 which engages the inner end of the carrier 13 as indicated in Figs. 3 and 5. The spring 38 is confined between the enlarged portion 39 of the pintle and a trunnion plate 42 that is journaled in bearing openings 43 in the ends of the arms 33. The pintle 38 extends through an opening in the trunnion plate 42.

When the switch is in the closed position shown in Fig. 3, it may be moved to the open position shown in Fig. 2 by moving the operating handle 31 in a clockwise direction, Fig. 3. This movement causes the trunnion plate 42 to move toward the enlarged portion 39 of the pintle and compress the spring 37. When the pivots of trunnion plate 42 pass beyond the plane of the carrier 13, the spring will expand and move the carrier to the open position with a snap action. To close the switch, the operating handle is moved in the opposite direction, thus causing the carrier to be moved to the closed position with a snap action. Lugs 44 on the wings 9 of the frame 7 serve to engage the arms 33 of the operat-

ing handle and limit the movement thereof in either direction.

By reason of the notch 12 being cut in from the base portion of the frame, the carrier 13 may readily be assembled therein. The parallel wings 9 of the frame 7 may be pressed toward one another so that the journal lugs 16 thereof may be assembled in the bearing openings 15. When the journals are brought into registry with the openings 15, the wings of the frame are released and return to their normal position. The arms remain in this position and prevent separation of the carrier from the frame.

By reason of the operating handle construction, the metal arms thereof may readily be assembled with respect to the insulating handle when the arms and handle are riveted to the frame. It will be apparent that the assembly of the entire switch unit is relatively simple and is an inexpensive operation.

While few parts are required, it is apparent that a sturdy construction is provided wherein the switch may be positively moved to the open position by the operating handle in the event that the switch blades become fastened to the contact members due to corrosion of the parts or fusion of the metal thereof.

It will be noted that the insulating plates 21 are so disposed that they are interposed between the switch blades and the contact members when the switch is in open position. In moving to open position, the insulating plates pass the contact members on opposite sides thereof and any arc formed between the ends of the switch blades and the contact members is drawn between the spaced insulating plates and is cooled and rapidly extinguished before any burning of the switch blades or contact members occurs.

The insulating plates also serve to prevent the arc from flashing over from adjacent switches or to any metal parts in the immediate vicinity of the switch.

While I have illustrated but one embodiment of my invention, it will be apparent to those skilled in the art that various changes, modifications, substitutions, additions and omissions may be made in the apparatus illustrated without departing from the spirit and scope of my invention as set forth in the appended claims.

I claim as my invention:

1. Switch mechanism comprising a frame member of U-shape having a base portion and integral wing portions and a notch extending inwardly through the base portion of the frame and a bearing portion adjacent the notch for receiving a switch carrier, a switch carrier of U-shape having inwardly extending journal members cooperating with the bearing portions for pivotally supporting the carrier for oscillation within the said

- notch, the carrier having inwardly projecting integral lugs extending through the notch into the space between the wings of the frame member, an operating handle pivotally mounted for oscillation between the said wings and having spaced arms provided with openings for receiving the said lugs, whereby the carrier is operated positively by the handle after the latter has moved in either direction a predetermined distance, and an over-center spring disposed between the said arms and the carrier for moving the carrier with a snap action in response to a predetermined movement of the said handle. 6 70 75 80 85 90 95 100 105
2. Switch mechanism comprising a switch member, a frame for supporting the switch member comprising a pair of spaced plates, an insulating operating handle for the switch member pivotally mounted between the plates upon a shaft connected to the said plates and having its opposite sides cut away near the inner end to form shoulders on opposite sides of the handle, and operating arms pivotally mounted upon the shaft on opposite sides of the handle, and fitting into the cut-away portions and engaging the shoulders for preventing relative rotary movement of the arms and handle. 15 20 25 30 35 40 45 50 55 60 65 70 75 80 85 90 95 100 105
3. Switch mechanism comprising a frame member of U-shape having a base portion and integral wing portions and a notch extending inwardly through the base portion of the frame and a bearing portion adjacent the notch for receiving a switch carrier, a switch carrier of U-shape having inwardly extending journal members cooperating with the bearing portions for pivotally supporting the carrier for oscillation within the said notch, the carrier having inwardly projecting integral lugs extending through the notch into the space between the wings of the frame member, an operating handle pivotally mounted for oscillation between the said wings and having spaced arms provided with openings for receiving the said lugs, whereby the carrier is operated positively by the handle after the latter has moved in either direction a predetermined distance, an over-center spring disposed between the said arms and the carrier for moving the carrier with a snap action in response to a predetermined movement of the said handle and means on the said wings for limiting the movement of the said arms in either direction. 30 35 40 45 50 55 60 65 70 75 80 85 90 95 100 105
4. Switch mechanism comprising an insulating support having a terminal on one face thereof, a switch base mounted upon the support and having a contact member having a terminal-engaging portion on its inner face for engaging the terminal on the support when the base is in assembled position on the support and having an integral switch contact portion exposed on the outer face of the base for engaging a switch member, and a movable switch member mounted on the outer face of the base for conductively engaging the said switch contact portion. 15 20 25 30 35 40 45 50 55 60 65 70 75 80 85 90 95 100 105
5. Switch mechanism comprising an insulating support having a terminal on one face thereof, a switch base mounted upon the support and having a contact member having a terminal-engaging portion on its inner face for engaging the terminal on the support when the base is in assembled position on the support and having an integral switch contact portion exposed on the outer face of the base for engaging a switch member, a movable switch member mounted on the outer face of the base for conductively engaging the said switch contact portion, and means for releasably clamping the base upon the support for maintaining the first said contact member in conductive engagement with the terminal on the support. 15 20 25 30 35 40 45 50 55 60 65 70 75 80 85 90 95 100 105
6. Switch mechanism comprising an insulating switch base having slots extending inwardly from an edge thereof, contact members having a switch contact portion exposed on one face of the base and an integral terminal contact portion on the other face of the base provided with a slot aligned with the slot in the base, a movable switch member mounted on the base for engaging the said switch contact portions, a support for the base having terminals on one face thereof adapted to be engaged by the said terminal contact portions when the base is in assembled position, and attaching screws on the base extending through the said slots in the terminal portions and the base for securing the base to the support. 15 20 25 30 35 40 45 50 55 60 65 70 75 80 85 90 95 100 105
- In testimony whereof, I have hereunto subscribed my name this seventh day of August 1928.
- HUBERT K. KRANTZ. 105
